DISPENSING CONTAINER

William Barton Smoot, Washington, D. C., assignor to Flo-Bar, Limited, New York, N. Y., a corporation of New York

Application June 7, 1949, Serial No. 3,098

Term of patent 14 years

(Cl. D86—10)

To all whom it may concern:

Be it known that I, William Barton Smoot, a citizen of the United States and a resident of Washington, District of Columbia, have invented a new, original, and ornamental Design for a Dispensing Container, of which the following is a specification, reference being had to the accompanying drawing, forming part hereof, in which:

Fig. 1 is a perspective view of a dispensing container embodying my new design; and

Fig. 2 is a side elevation thereof in section taken along lines 2—2 of Fig. 1.

I claim:

The ornamental design for a dispensing container, as shown.

WILLIAM BARTON SMOOT.
